UNITED STATES PATENT OFFICE.

THOMAS FRED FITZBERGER, OF BALTIMORE, MARYLAND.

ASH-SIFTER.

1,351,377.

Specification of Letters Patent. Patented Aug. 31, 1920.

Application filed January 13, 1919. Serial No. 270,813.

To all whom it may concern:

Be it known that I, THOMAS FRED FITZBERGER, a citizen of the United States, residing in the city of Baltimore and State of Maryland, have invented and discovered certain new and useful Improvements in Ash-Sifters, of which the following is a specification.

My said invention consists in certain improvements in the details of construction and arrangements of parts of ash sifters for household and other use, whereby the operation of sifting ashes may be conducted with little, if any, discomfort incident to dust and dirt and the ashes sifted in a most efficient manner, all as will be hereinafter more fully described and claimed.

Referring to the accompanying drawing, which is made a part hereof and on which similar reference characters indicate similar parts;

Figure 1 is a view of an ash sifter constructed in accordance with my said invention, a portion of the body or casing being broken away to show the interior, and

Fig. 2, a cross section looking in the direction indicated by the arrows from the dotted line 2—2 in Fig. 1.

In said drawing the portion marked A represents the main body of the sifter; B the cover therefor and C, the sifter floor or bottom.

The parts A and B are not any peculiar construction or arrangement, but may be such as are appropriate for the purpose. The sifter is preferably made of sheet iron, cylindrical in form, and the cover B is formed to fit tightly and prevent the escape of dust during operation. The lower edge of said cover preferably fits against a bead formed to project around the body A, near its top. The lower end 12 is somewhat larger than the body A, being formed with an offset 13, and is adapted to fit over the top of a barrel 14, or other receptacle for the ashes, or a chute leading to a point of discharge for said ashes.

A door 15 is mounted over an opening formed in the front side of the body A, being adapted to slide vertically behind flanges 16, appropriately secured to said body on each side of said opening. Said door is provided with a handle 17 by which it is operated.

A spout or chute 18 is mounted to receive the discharge and leads from said opening,

the floor thereof being in line with the lower edge of the opening and otherwise appropriately arranged for conducting the cinders from the sifting floor to an appropriate receptacle placed under said spout.

The sifting floor C is a circular perforated plate, as shown most clearly in Fig. 2, and is supported on brackets 19 distributed at intervals around the body A on the inside thereof and in a position so that the edge of said floor adjacent to the spout 18 will be substantially in line therewith and its rear edge considerably elevated above said spout, thus disposing said sifting floor at an inclination across said body. The rear of said floor is provided with a handle 20 which extends through a segmental slot 21 in the rear side of said body, as shown. A curved plate 22 is mounted on the rear edge of said sifting floor C covering slot 21 so as to prevent the escape of the ashes and dust to said slot. Said plate is held in position by engaging flanges 23 secured to the inner surface of body A, as plainly shown in Fig. 1.

In operation the ashes containing the cinders, ready for sifting, are placed in the receptacle A and the cover B placed in position. The operator then oscillates the sifting floor C by means of the handle 20 which serves to cause the fine ashes to pass through the perforation into the receptacle below and retain the cinders and coarse material on the top of the floor.

It will be noted that the sifting floor C is formed convex with its curved face uppermost, and this feature of construction plays an important part in the operation of the apparatus in that it makes all parts of the sifting floor active. As will be understood, the center of said floor if flat would have no movement and would be comparatively inactive for sifting purposes.

After the ashes have been thoroughly separated from the cinders the operator lifts door 15 and permits the cinders to slide down the spout 18 into the receptacle provided therefor. This operation may be assisted by tilting body A, or by a rake provided for the purpose.

Having thus fully described my said invention, what I claim as new and desire to secure by Letters Patent is

1. An ash sifter comprising a cylindrical casing, a cover therefor, a downwardly inclined chute located upon one side of the

- casing and communicating with an opening in the side thereof, a sieve disposed within and extending in an inclined plane substantially in line with said chute entirely across 5 the casing and positioned to discharge at its lower side through the opening and upon the chute, means for supporting said sieve at its periphery within the casing, and a handle attached to said sieve and extending 10 through a segmental slot in said casing opposite said chute for oscillating said sieve.
2. An ash sifter comprising a cylindrical casing, a cover therefor, a downwardly inclined chute located upon one side of the 15 casing and communicating with an opening in the side thereof, a slidable closure for the opening, a sieve formed with a convex top surface disposed within and extending in an inclined plane substantially in line with said 20 chute entirely across the casing and positioned to discharge at its lower side through

the opening and upon the chute, means for supporting said sieve at its periphery within the casing, a handle attached to said sieve and extending through a segmental slot in 25 said casing opposite said chute for oscillating said sieve, a plate covering the slot in the casing through which said handle extends and carried by said handle, and an overhanging flange covering the edge of said 30 plate whereby said slot is closed against the escape of dust and ashes, substantially as set forth.

In witness whereof I have hereunto set my hand and seal at Baltimore, Maryland, 35 this 30th day of December, A. D. nineteen hundred and eighteen.

THOMAS FRED FITZBERGER.
